UNITED STATES PATENT OFFICE.

JAMES H. VAN TASSEL AND OLIVER P. HIPPLE, OF ELMIRA, NEW YORK.

ACETYLENE-GAS LAMP.

SPECIFICATION forming part of Letters Patent No. 655,840, dated August 14, 1900.

Application filed May 13, 1899. Serial No. 716,766. (No model.)

To all whom it may concern:

Be it known that we, JAMES H. VAN TASSEL and OLIVER P. HIPPLE, citizens of the United States, residing at Elmira, in the county of Chemung and State of New York, have invented certain new and useful Improvements in Acetylene-Gas Lamps; and we do declare the following to be a full, clear, and exact description of the invention, such as will enable others skilled in the art to which it appertains to make and use the same, reference being had to the accompanying drawings, and to the figures of reference marked thereon, which form a part of this specification.

15 Our invention relates to acetylene-gas lamps; and its primary object is to provide a lamp of this character which will be especially well adapted for use as a bicycle-lamp, although not restricted, of course, to that particular use.

The invention aims to provide a simple and inexpensive acetylene-lamp which will be self-regulating and so constructed as to be readily charged and cleaned and capable of generating and supplying to its burner a gas of superior quality.

The novel features of the invention will be fully described hereinafter and clearly defined in the appended claims, in connection 30 with the accompanying drawings, which form a part of this specification, and in which—

Figure 1 is a sectional elevation of a lamp embodying our invention, and Fig. 2 is a top plan view thereof.

35 The reference-numeral 1 designates a cylindrical shell or casing externally screw-threaded at its lower end and closed by a head 2, formed with an annular vertical flange 3, which is internally threaded to engage the 40 threads of the casing. The casing is divided by horizontal flanged partitions 4 and 5 into three compartments 6, 7, and 8, constituting, respectively, a generator-chamber, a water-chamber, and a light-chamber. Within the 45 lower compartment 6 is located a box or holder 9 for containing calcium carbid. The bottom of this carbid-holder is formed with a central opening to fit over a screw 10, which extends through a central opening in the head 2 and 50 has its head soldered or otherwise permanently secured within a beveled seat 11,

formed in the head 2. The top of the carbid-holder is closed by a cover 12.

13 designates a tubular casing arranged centrally within the carbid-holder and closed at its lower end by a plug 14, which is centrally bored and threaded to fit the screw 10. The tube 13 is perforated for the passage of water therethrough and surrounded by a covering 15, of wire-gauze, to prevent the particles of carbid from adhering to the tube or stopping up the openings therein. The upper end of the tube 13 extends through a central opening in the cover 12, and within said tube is suspended a perforated water-supply pipe 16, 65 the upper end of which extends through the partition 4 and is secured within an opening in a diaphragm 17, located above the partition 4 and parallel thereto. Between the partition 4 and diaphragm 17 the main casing is formed 70 with a series of ventilating-openings 18.

The compartment 7 constitutes the water-chamber of the lamp, provided with a filling-tube 19, the upper end of which is closed by a screw-cap 20, having an air-hole 21 to facilitate the downward feed of water. Resting upon the diaphragm 17, which forms the bottom of the water-chamber, is a horizontally-arranged valve-casing formed with a water-inlet 22, and an outlet 23, the latter 80 registering with the upper end of the water-feed pipe 16 and the former being controlled by a needle-valve 24, fitting the conical seat of the valve-casing, and having a screw-stem 25 and handle 26, the valve-casing being internally threaded to engage said valve-stem. 85

The feed-pipe 16 is formed at diametrically-opposite points with openings 27 for a purpose hereinafter explained.

28 designates a gas-supply pipe the upper 90 end of which extends through an opening in the partition 5 to register with a burner tube or thimble 29. The body of the pipe is inclined toward the side of the casing, and its lower end extends down through the bottom 95 of the water-chamber and through the partition 4 to connect with a gas-passage 30, formed by a pressed plate 31, soldered to the wall of the casing, and closed at its lower end by a filtering-plug 32, of sponge, felt, or like 100 material, which serves to filter and purify the gas in its upward passage. The plate 31 is

of curved or circular shape in cross-section and enlarged at its upper end to form a chamber 31^a, into which the lower end of the pipe 28 projects. The upper edge of the enlarged portion of the plate 31 is formed with a horizontal flange 31^b, which is soldered to the under side of the partition 4, the vertical edges of the plate being soldered to the wall of the casing, as above stated. This construction enables the parts to be assembled in proper relative positions without any fitting or special connection between the lower end of the pipe 28 and the gas-passage 30, and the chamber 31^a affords a free feed of the gas upward through the pipe 28 to the burner.

Within the tube or thimble 29 is located a burner 33, preferably a double burner of the form shown. In rear of the burner 33 within the light-chamber 8 is secured a reflector 34, and in front of said burner is a lens-holder 35, supporting by any suitable means a lens 36.

37 designates draft-openings formed in the casing just above the partition 5, and the upper end of the light-chamber 8 is closed by a dome 38, formed with ventilating-openings 39. The light-chamber is also preferably provided with side openings containing colored and ornamented glass 40, as is common in bicycle-lanterns.

30 A gasket 41, of rubber or like yielding material, is interposed between the bottom of the carbide-holder and head 2.

42 designates parallel lugs projecting from the casing for attaching the lamp to a bicycle.

35 The operation of the generator and lamp constructed as above described is as follows: The water under control of the valve feeds down through the supply-pipe 16 and percolates therethrough to the tube 13, through the 40 perforation of which it passes to the carbide within the holder to generate the gas. The gas rises through the tube 13 and finds its way to the lower end of the passage 30, through which it rises to the pipe 28, from whence it 45 passes to the burner, being filtered and purified in its passage through the filtering material 32. In case more water than is necessary is supplied to the carbide-chamber, resulting in an undue or excessive generation 50 of gas, a back pressure is immediately established through the openings 27, which acting upon the water-feed opening 23 in the valve-casing stops the inflow of water until the normal gas-pressure is again restored and

allows such excess gas to pass up through the 55 water-chamber and escape with more or less water through the tube 19.

It will be observed that all of the operative parts of the lamp are contained within a single integral casing, that the construction of 60 the devices for supporting the carbide-chamber and water-supply tube is such that by unscrewing the head 2 the carbide-chamber and water-supply tube may be quickly removed for recharging or cleansing, and that 65 the space between the water-chamber and generating-chamber is ventilated to prevent the heat from the generator overheating the water in the water-chamber.

A further advantage of our construction is 70 that the gas is carried down around the outside of the carbide-chamber on its way to the gas-passage, and is thus more or less heated, with the result that the gas is dried before being supplied to the gas-supply pipe and 75 burner.

We claim—

1. In an acetylene-gas lamp, the combination with a casing divided by horizontal partitions, of a carbide-holder in the lowermost 80 compartment, a gas-passage arranged at one side of the carbide-holder and comprising a plate secured to the wall of the casing and extending above and below the top of the carbide-holder, to cause the gas to be directed 85 downwardly around said holder, and then upward to the burner-supply pipe, the lower end of the latter extending into said gas-passage.

2. In an acetylene-gas lamp, the combination with a casing divided by horizontal partitions, of a carbide-holder in the lowermost 90 compartment, a gas-passage arranged at one side of the carbide-holder and comprising a plate secured to the wall of the casing and to 95 the under side of the adjacent horizontal partition, and enlarged at its upper end to form a gas-chamber and a burner-supply pipe the lower end of which extends through said partition and projects into said gas-chamber. 100

In testimony whereof we affix our signatures in presence of two witnesses.

JAMES H. VAN TASSEL.
OLIVER P. HIPPLE.
